VARIABLE SPEED IMPACT MACHINE

Robert K. Haskell and Harold C. Mann,
Watertown, Mass.

Application July 29, 1938, Serial No. 221,967

5 Claims. (Cl. 265—13)

(Granted under the act of March 3, 1883, as
amended April 30, 1928; 370 O. G. 757)

The invention described herein may be manufactured and used by or for the Government for governmental purposes, without the payment to us of any royalty thereon.

5 The subject of this invention is a variable speed impact machine for testing material to the breaking point by impact.

The main object of the invention is the provision of a device in which the impact element is 10 moving at a predetermined speed at the instant of impact and one in which the force of impact will be indicated.

15 The invention resides broadly in the provision of a rotary member carrying a centrifugally extruded striker or hammer, with means for locking the hammer in retracted position and a pendulum means for carrying the test specimen.

20 More specifically the invention consists in spaced rotatable disks between which is pivotally mounted a centrifugally actuated striker, normally locked in retracted position by a lock bar extending diametrically between the disks and rotated by suitable gearing to locked and unlocked position, with releasable means for actuating the 25 gearing at desired times, and a pendulum for mounting a test specimen in the path of the striker or hammer when extended.

25 A practical embodiment of the invention is shown by way of illustration in the accompanying drawings, wherein,

30 Fig. 1 is a view in side elevation of the device, parts broken away;

Fig. 2 is a view in end elevation with parts in section.

35 Fig. 3 is an enlarged view in side elevation of the rotatable disks parts broken away and parts in section on the line 3—3 of Fig. 2;

Fig. 4 is a sectional view of the central shaft;

Fig. 5 is a plan view of the striker;

40 Fig. 6 is a sectional view on the line 6—6 of Fig. 3;

Fig. 7 is a sectional view on the line 7—7 of Fig. 6.

45 Referring to the drawings by numerals of reference:

There is provided a suitable base 1 upon which the spaced uprights 2 are mounted the upper portions of which are adapted to receive the hollow shaft 3 which is journaled therein.

50 The shaft 3 is formed centrally with an annular flange 4 to each side of which is an enlarged portion or hub 5 adapted to receive the discs 6 which are keyed to the respective hubs as at 7 and are spaced apart by the flange 4.

55 Hollow studs 8—8 fixed to the inner faces of the

uprights 2 and surrounding the shaft 3 receive the bearings 8^a of a pendulum member which consists of sides 9 depending from the bearings and having their lower ends connected by a cross plate 10. A plate 11 mounted as by bolts 12 on the cross plate 5 10 is formed with a slot for the reception of a specimen holder 13 which may be secured in place by the bolt 14 and which is conveniently provided with a handle 15 for removal of the holder when the bolt is unscrewed. There is shown mounted 10 in the holder a shear type specimen 16 with the usual tup 17, but it is to be understood that other type specimens may be substituted therefore.

Mounted for oscillation on one of the studs 8 15 and adjacent to one side plate of the pendulum is a pointer 18 which is adapted to be contacted by a finger 19 carried by the pendulum so that the pointer will be carried by the pendulum on its initial upward swing under the force of a blow on the tup 17 and will remain in such position 20 through frictional contact until moved manually to its normal position.

A scale 20 may be carried by an upright 2 against which the pointer 18 is read to indicate 25 the force of the blow delivered to the tup carried by the test specimen.

Inserted in the hollow shaft 3 (Fig. 4) to slide axially thereof is a shaft 21 provided with a key 22 to fit in a keyway 23 of the shaft 3. Secured in the outer end of the shaft 21, as by a pin 24, is 30 a plug having a threaded portion 25 and a head 26. Mounted on the threaded portion 25, and normally in engagement with the head 26 and the end of the shaft 3, is a cam nut 27. A removable stop 28 is inserted in an aperture formed in the 35 shaft 3 and extends into the keyway 23 to limit the outward throw of the shaft 21.

Encircling the shaft 3 with its outer face flush with the end of said shaft is a ring 29 formed with a flat 30 (Fig. 3) in its periphery. This ring is 40 held in place on the shaft as by a set screw 31 the pointed end of which seats in an annular groove 32 formed in the shaft 3.

Attached to a standard 2 in any suitable manner is a plate 33 (Fig. 3) upon which is pivotally 45 mounted a lever 34 pressed by a plunger 35 toward the ring 29. The plunger 35 is mounted in a casing 36 carried by the plate 33 and is urged by a spring 37 toward the lever 34.

A suitable latch is provided for holding the 50 lever 34 against the action of the plunger 35, the same, as herein shown consisting of a plunger 38 mounted in a housing 39 carried by the plate 33 and urged by a spring 40 to a position beneath the free end of the lever 34. The outer end of the 55

plunger 38 is provided with a knob 41 and which may be grasped to withdraw the plunger from its position beneath the lever 34.

The lever 34 includes a bell crank arm or finger 42 adapted to normally engage a dog 43 pivoted to an extension 44 of a housing 45 in which there is a plunger 46, the inner end of which is forced against the dog by a spring 47. The dog 43, when released by the detaining finger 42 through swing of the lever 34 is adapted to engage the lip 48 on the cam nut 27 to hold the same against rotation with respect to the shaft 21 and to thereby cause the shaft, through the action of the threads, to be drawn to the left as viewed in Figs. 2 and 4. A knob 49 may be provided on the outer end of the plunger 46 for convenience in setting the device.

The shaft 21 has formed on its inner end a rack 50 meshing with a pinion 51 on a rod 52 which extends diametrically between the discs 6, passing through the hollow shaft 3 and mounted in the brackets 53 carried by the discs. The opposite ends of the shaft 52 are provided with means for releasably holding a striker or hammer 54 and a somewhat similar counterbalance 55 each of which is pivotally carried by and between the discs adjacent the periphery thereof. The holding connections are similar and are illustrated in detail in Figs. 6 and 7 in which the hammer, for example, is provided with a cylindrical opening 56 having opposite slots 57 to provide clearance. Interrupted teeth 58-58 formed in opposite walls of the opening 56 are adapted to be engaged by interrupted teeth 59-59 on opposite sides of the rod 52. When the shaft is turned 90 degrees the teeth 59 are disposed in the slots 57.

The striker or hammer 54 may be of any suitable form, the one herein shown being fashioned with an extension 60 extending radially from a hub 61, and with a short diametrically opposite extension 62 in which the opening 56 is provided. The extension 62 lies between the striking elements 63-63 which are spaced apart and which extend into recesses 64-64 formed in the respective inner faces of the discs. The walls 64a and 64b defining each recess are engageable by opposite sides of the striking elements 63-63 and serve as stop surfaces.

The counterbalance 55 is of similar construction with the exception that the spaced members 65-65 which lie in recesses 66-66 formed in the inner faces of the discs 6 when in rotated position, do not extend beyond the periphery of the discs.

In preparing the machine for operation the parts are in the positions shown in full lines in Figs. 3 and 4, the hammer and the counterweight being held in retracted position, the dog 43 held out of engagement with the lip 48 on the nut 27, and the shaft 21 moved to the right with the head 26 in engagement with the nut.

In operation the discs 6 and shaft 3 are rotated by any suitable power until a desired speed is attained whereupon the knob 41 is grasped and the plunger 38 withdrawn to release the lever 34. The lever 34 is now free to be moved into contact with the periphery of the ring 29 where it drops onto the flat 30 and the finger 42 is moved to further retract and then release the dog 43. The dog 43 is now moved by the plunger 46 into engagement with the nut 27 where it engages the lip 48 of the nut 27 and holds the nut stationary.

The shaft 21 which is being rotated by virtue

of its connection with the shaft 3 through key 22 is unthreaded from the nut and displaced to the left until the key 22 engages the stop 28. During this displacement the rack 50 imparts a quarter turn to rod 52 to move the teeth 59 clear of the teeth 58 and release the hammer and counterweight. The hammer under the influence of centrifugal force acting on the heavier extensions 63 is rotated to the extended position shown in dotted lines in Fig. 3 where the striking elements 63 are supported by the stop surfaces 64b and impact the tup 17.

When the hammer strikes the tup which is carried by the pendulum the latter is oscillated and the amount of oscillation transmitted by the finger 19 to the pointer 18 which is read against the scale 20 and thereby indicates the force of impact delivered to the tup and the test specimen.

We claim:

1. A variable speed impact machine embodying a support, a hollow shaft journaled in the support, spaced discs carried by the hollow shaft, a hammer disposed between the discs and pivoted therein, a counterbalance pivotally carried by the discs oppositely to the hammer, a rod passing through the hollow shaft diametrically of the discs, interrupted teeth on the opposite ends of the rod, interrupted teeth on the hammer and on the counterbalance and engageable by the teeth on the rod to hold the hammer and counterbalance in retracted position within the periphery of the discs, means for rotating the rod to disengage its teeth from the hammer and counterbalance and release these members for rotation under the influence of centrifugal force upon rotation of the disc, and a pendulum adapted for mounting a test specimen in the path of the released hammer.

2. A variable speed impact machine embodying a support, a rotatable element journaled in the support, a normally retracted hammer carried by the element, a rod for holding the hammer in retracted position against the influence of centrifugal force tending to extend it, a shaft movable axially of the rotatable element, and rotatable therewith, gearing between the shaft and rod to move the rod into locking and unlocking relation to the hammer, said element having a flat, a nut threaded on the shaft, a dog carried by the support and movable into engagement with the nut to hold the nut against rotation, a lever engageable with the shaft and movable onto the flat of the element to release the dog, a latch for holding the lever off of the flat, and a pendulum adapted for mounting a test specimen in the path of the hammer when extended.

3. A variable speed impact machine embodying a support, a rotatable element journaled in the support, a normally retracted hammer carried by the element, a rod for holding the hammer in retracted position against the influence of centrifugal force tending to extend it, a shaft movable axially of the rotatable element and rotatable therewith, gearing between the shaft and rod to move the rod into locking and unlocking relation to the hammer, mechanism adjacent the shaft and cooperating when manually released with means on the shaft to automatically displace the shaft axially to rotate the rod, and a pendulum adapted for mounting a test specimen in the path of the hammer when extended.

4. A variable speed impact machine embodying a support, a rotatable element journaled in

the support, a normally retracted hammer carried by the element, a rod for holding the hammer in retracted position against the influence of centrifugal force tending to extend it, a shaft movable axially of the rotatable element, and rotatable therewith, a connection between the shaft and rod whereby axial displacement of the shaft moves the rod to release the hammer, means for axially displacing the shaft, manually operable means for controlling actuation of said preceding means, and a pendulum adapted for mounting a test specimen in the path of the hammer when extended.

5. A variable speed impact machine embody-

ing a support, a hollow shaft journaled in the support, a rotatable element carried by the hollow shaft, a normally retracted hammer carried by said element, a member disposed radially of said element for holding the hammer in retracted position against the influence of centrifugal force tending to extend it, means within the hollow shaft for actuating said member to release the hammer, and a pendulum adapted for mounting a test specimen in the path of the released hammer.
